FURNITURE CONSTRUCTION

Steve J. Repaich, Los Angeles, Calif., assignor to California Quilt Furniture Corporation, Los Angeles, Calif., a corporation of California

Application December 12, 1955, Serial No. 552,528

3 Claims. (Cl. 155—191)

This invention has to do with furniture construction and while, in its broader aspects, it is advantageously adaptable to various articles of furniture, it is particularly useful in upholstered and padded chair construction.

In the manufacture of padded and upholstered furniture, such as chairs and settees, it has always been conventional practice to utilize only a wood frame to which the side and back rest springs are attached by anchor members nailed to the frame. Then the padding is applied and the upholstery is nailed to the frame over the padding. However, when such a frame is subjected to diagonal stresses it becomes permanently warped because the wood frame does not have that resiliency so necessary to cause it to return to its original shape when the diagonal stresses are relieved.

Also, the attachment of the springs to such a wood frame is not only time consuming and costly, but also, due to splitting of the wood, the springs often become detached from the frame in spots, causing sagging.

Another objectionable feature of such wood frames is that it often becomes necessary to cut the frame elements into complicated shapes to provide for varied contours. Wood frames also possess other objectionable features. For instance, the screws and nails used to secure the frame members together often work loose as various stresses are applied to the frame.

It is an object of my invention to provide a construction which overcomes those disadvantages of wood frames but which, at the same time, achieves all the advantages inherent in wood frames.

More particularly, it is an object to provide a chair construction which utilizes a unitary inner metallic frame provided with means for easily and securely anchoring the springs as well as contouring elements thereto, and which also utilizes an outer wood frame capable of damping any metallic sounds emanating from the metallic frame in the course of use. In my novel construction the normal stresses incident to use are absorbed by the metallic inner frame without any injury to the outer, wood frame.

Another object is to provide a construction which is conducive to efficient utilization of vibrator elements, since in my construction the vibrator elements may be attached directly to the metallic inner frame portion so that all the resultant vibrations are efficiently transmitted to the occupant, while the wood outer frame damps the sounds which might ordinarily be produced by such vibrations.

Other objects and corresponding advantages will appear hereinafter.

Without intending thereby to limit the broader aspects of my invention, except as may appear from the appended claims, but rather for explanatory purposes only, I shall now describe in detail a presently preferred embodiment of my invention, for which purpose I shall refer to the accompanying drawings wherein,

Fig. 1 is a side elevation with parts of the wooden outer frame removed for illustrative purposes;

Fig. 2 is a front elevation;

2

Fig. 2A is an enlarged section on line 2A—2A of Fig. 2;

Fig. 3 is an enlarged fragmentary section taken on line 3—3 of Fig. 1;

5 Fig. 4 is a perspective view of a portion of the metallic frame element;

Fig. 5 is a perspective view showing the seat and back rest portions of my frame;

Fig. 6 is an enlarged section taken on line 6—6 of 10 Fig. 5; and

Fig. 7 is an enlarged fragmentary section on line 7—7 of Fig. 5.

Referring now to the drawings, I show at 5 what I term the inner base frame comprising rectangular side frame elements 15 each composed of angle iron strips 16 welded together, and bottom cross-members 17, members 17 likewise being of angle iron welded at their ends to the elements 16.

20 A pair of posts 20 are welded at their bottom ends to the bottom portion of the frame elements 15, and a seat supporting rod 19 is welded at its ends to the top ends of the posts. The numeral 30 generally denotes the unitary inner seat and back rest frame, likewise composed of angle iron strips and comprising side elements 32 and 25 cross strips 34. Holes 35 are provided in certain of the cross strips 34 for the reception of the hooked ends 37A of springs 37; while holes 38 are provided in those portions of the side elements 32 which define the sides of the back rest, for the reception of the hooked ends of springs 39. Metallic contouring strips 40 and metallic bracing strips 42, 43 are welded to the side elements 32.

Those portions of the side elements 32 which in part define the seat frame have bosses 45 screwed or welded thereto and depending therefrom, the bottom surface 35 of each boss being notched at 46 to receive the rod 19, thus enabling the seat and back rest frame to be tilted about the rod 19 relative to the base frame. To prevent the seat and back rest frame from being lifted from the rod 19, I provide a pair of retaining plates 47 each of 40 which has an opening to rotatably receive the rod 19, and the respective plates 47 are screwed to the sides of the respective bosses 45.

The metallic base frame 5 is also provided with bracing strips 50 welded to the base frame, while the frame 45 30 has bracing strips 51 welded thereto.

Secured to the metallic base frame 5, I provide wood strips, now to be described, which define an outer base frame as well as provide a foundation to which the upholstery, indicated by broken lines U, may be tacked or nailed. A further function of the wood outer base frame is to damp any metallic sounds which might be generated by the metallic inner base frame. For instance, the base frame elements 15 have wood nailing strips 60, 61 secured thereto as by screws 62. Wooden bottom strips 65 are secured in like manner to the bottom portions of the frame elements 15 and front upright wooden strips 66 and side upright wooden strips 67 are secured to the strip 65. Ears 68, welded to the base frame upright 15 facilitate attaching certain of the wooden 65 strips thereto.

Frame 30 also has wooden strips 70, 71 secured thereto as by screws 73. The bottom ends of the strips 70 and the rear top edge portion of strips 67 are diagonally cut at 70A, 67A to facilitate swinging of the back rest relative to the base.

While I have described a preferred manner of arranging the outer wooden frame elements about and securing them to the inner frame elements, it will be understood that various specific attaching means may be utilized so long as the metallic inner frame elements are arranged within the outer frame elements and so long as the wooden frame elements are positioned to provide founda-

tion or nailing surfaces for the reception of the upholstery nails. The positioning of the wood nailing strips of course may be varied according to the requirements of any given upholstery job. For instance, in Fig. 5 I denote additional wood cross nailing strips 74.

After the framework is constructed as described and the spring elements 37, 39 installed, the desired padding may be applied and covered by upholstery as desired.

While I am aware that heretofore it has been proposed to incorporate vibratory elements in chairs for health and relaxation purposes, it has been my observation that the incorporation of such vibratory elements in chairs embodying only wood framework has not been conducive to obtaining maximum beneficial results from the vibratory element, due to the fact that vibrations are not transmitted through the wood with much efficiency. However, I find that by utilizing my inner metallic frame construction in conjunction with wooden outer frame construction, I am able to incorporate a conventional vibratory element in the metallic frame construction in such manner that the full effect of the vibrations is transmitted throughout the seat and back rest inner frame.

For instance, in Figs. 1 and 2 I show a conventional eccentric type, electrically driven vibratory element 80 rigidly fixed to a metallic strap 81. The bottom end of the strip is rigidly secured to a metallic cross strip 82 which latter strip is in turn welded or otherwise rigidly secured at its ends to the side members 32 of the unitary inner seat and back rest frame, while the top end of the strap is secured to a plurality of springs 39 by clamping plates 85 and bolt 86.

From the foregoing it will be apparent that by my invention I have provided a chair construction which is practically unbreakable under all normal conditions of use, which will not warp when subjected to abnormal stresses, which is conducive to economical construction, which is extremely durable, which provides a reclining chair in which the relatively movable parts will not get out of alignment, in which the spring elements are anchored to the frame in such manner that they do not pull away, in which the stresses resulting from use of the chair in reclining position are imposed upon the metallic inner frame elements exclusively, and in which a vibratory element may be incorporated with maximum efficiency.

I claim:

1. In chair frame construction, the combination of angle iron strips welded together to define a unitary metallic inner base frame, wood strips secured to and disposed outside said base frame to define an outer base frame, angle iron strips welded together to define a

4
unitary inner seat and back rest frame, wood strips secured to and disposed outside the back rest portion of said latter frame to define an outer back rest frame, means supporting said inner seat and back rest frame from said inner base frame, said latter means comprising a bar of round cross-section disposed transversely of said inner base frame, posts supporting said bar from said base frame, bosses depending from said inner seat and back rest frame and resting against said bar and plates rotatably carried by said bar and secured to said bosses.

2. In chair frame construction, the combination of metal strips welded together to define a unitary metallic inner base frame, wood strips secured to and disposed outside said base frame to define an outer base frame, metal strips welded together to define a unitary seat and back rest frame, wood strips secured to and disposed outside the back rest portion of said latter frame to define an outer back rest frame, and means supporting said inner seat and back rest frame on said inner base frame including a transverse metal member on said inner base frame and pivotal connection means between said transverse metal member and said inner seat and back rest frame.

3. In chair frame construction, the combination of a metal base frame, a metal unitary seat and back rest frame, and means supporting said seat and back rest frame on said base frame, comprising a bar of round cross-section disposed transversely of said base frame, posts supporting said bar on said base frame, bosses depending from said seat and back rest frame and resting against said bar, and plates rotatably carried by said bar and secured to said bosses.
